RETORT, TANK, OR LIKE CONTAINER

Eugene Augustus Blount, Sr., Athens, Ga.

Application April 12, 1945, Serial No. 588,039

5 Claims. (Cl. 220—36)

1

This invention relates to retorts, tanks, and similar vessels or containers of the type having closures that can be sealed to hold pressure or vacuum, and more particularly to an improved cover or lid and mounting therefor.

One of the objects of the invention is to insure that the cover or lid shall be in the correct position for closing and sealing after the retort, tank or the like has been charged.

Another object is to open the cover automatically a sufficient amount to disengage the sealing means between it and the container, thereby preventing damage to gaskets, gasket seats, and like sealing means.

A further object is to reduce the manual effort required to handle the cover in an apparatus of the type characterized above.

A still further object is to provide for automatic opening of the cover in such a manner that steam or the like escaping from the container is least likely to injure the operator.

Still another object is to replace the cover on the container in exactly the same position from which it was removed when the container was opened.

Other objects will appear hereinafter as the description of the invention proceeds.

One embodiment of the invention has been illustrated in the accompanying drawings, but it is to be understood that these drawings are for purposes of illustration only and are not to be taken as a definition of the limits of the invention, reference being had to the appended claims for this purpose.

In the drawings,

Fig. 1 is a plan view of apparatus embodying the invention;

Fig. 2 is a section on the line 2—2 of Fig. 1;

Figs. 3 and 4 are details of means for mounting the cover, Fig. 3 being a section on the line 3—3 of Fig. 1; and

Figs. 5 and 6 are details showing suitable means for securing the cover in closed position, Fig. 5 being a section on the line 5—5 of Fig. 1.

In the form shown, the invention is embodied in a tank or retort 1 having an open top adapted to be closed by a cover or lid 2 hinged at one side of the tank. Suitable means are provided for sealing the cover to the tank, said means preferably comprising a tongue and groove type of seal between cooperating elements on the tank and cover. As shown, a ring 3 surrounds the top of the tank and is suitably secured thereto as by welding, the ring projecting above the top of the tank at 4. A ring 5 is suitably secured to the cover 2 as by welding and is grooved at top and bottom as indicated at 6 and 7 respectively. When the cover is closed, the groove 7 fits over the projecting rim 4 of the ring 3, forming a sort

2

of tongue and groove seal in which any suitable type of gasket can be used if desired.

The cover 2 is secured in closed and sealed position by suitable fastening means such as the clamps shown in detail in Figs. 5 and 6. Pairs of lugs or ears 8 are carried by the ring 3 at points spaced around the circumference of the tank. Clamping members 9 are pivoted one between each pair of lugs 8 by means of pins 10, the clamps projecting radially inward over the ring 5 and being provided with screws 11 the lower ends of which engage in the groove 6. It will be evident that when the screws 11 are backed off sufficiently, the clamps 9 can be swung outwardly on their pivot pins 10 so as to be out of the way when the cover is opened or closed. On the other hand, setting up the screws 11 with the clamps in the position shown in Fig. 5 forces the cover 2 down on the tank and seals and locks it in place.

It will be seen that before the cover 2 can be swung on its hinge to the completely open dotted line position shown in Fig. 2, it must first be lifted vertically to an elevated position also shown in this figure in order to disengage the sealing means, and also that the cover cannot be swung on its hinge to completely closed position but only to the aforesaid elevated position from which it must descend vertically on to the tank. To these ends the cover is counterbalanced about its hinge axis so that it naturally maintains a horizontal position, and the hinge axis is arranged for vertical upward movement under the influence of resilient means so that when the clamps are released, the cover automatically assumes the horizontal elevated position shown in Fig. 2.

These ends are achieved in the form shown by the construction illustrated in detail in Figs. 3 and 4. The ring 3 carries a pair of spaced hinge brackets 12 at one side of the container. A pin 13 extends through openings in the lower ends of these brackets, and carries between the brackets a sleeve 14 on which a spring seat 15 and guide 16 are mounted. The upper ends of the hinge brackets are slotted at 17 and a hinge pin 18 extends through the slots, being thus capable of vertical movement. Between the brackets the pin 18 carries a sleeve 19 on which are mounted a spring seat 20 and spring guide 21. A spring 22 is interposed between the seats 15 and 20 with the guides 16 and 21 projecting within its coils, so that the hinge pin 18 is resiliently mounted and normally maintained at its uppermost position limited by the upper ends of the slots 17.

The cover 2 is pivotally mounted on the hinge pin 18 by means of a U-shaped hinge member 23 the legs of which have openings through which the pin extends. The hinge member is secured to the cover in any suitable way, as by an integral extension 24 welded to the cover. A counterweight 25 is carried by an arm 26 which also is

suitably secured to the hinge member 23, as by means of screws 27. The counterweight is adjusted so as to counterbalance the cover 2 about the axis of the hinge pin 18.

When the tank is being charged, the cover is maintained in the dotted line position of Fig. 2 by the counterweight 25. On closing, the cover and counterweight are first swung to the horizontal elevated position shown in full lines in Fig. 2, in which they remain due to the counterbalancing action. The clamps 9 are now swung up to the position shown in Fig. 2 and the screws 11 are set up to force the cover vertically downward and engage the sealing means 4, 7. This downward movement is permitted by the slots 17, in which the hinge pin 18 moves downward compressing the spring 22 until the cover is sealed and locked in place.

When the tank is to be opened, the screws 11 are backed off, and as this takes place the spring 22 elevates the hinge pin 18 and with it the cover and counterweight, the latter elements tending to maintain their horizontal counterbalanced position. The clamps are then moved out of the way and the cover swung about its hinge to the full open dotted line position.

It will be observed that the cover is thus elevated automatically to disengage the sealing means before it is swung about its hinge axis. Moreover, the relative movement of the sealing means as they approach and separate from one another is essentially vertical, without any appreciable lateral sliding or dragging movement which would tend to injure the sealing means. Also the cover always returns to the tank in exactly the same position previously occupied. On the other hand, the operator naturally stands in front of the tank, and if he first backs off the screws 11 nearest the hinge, the seal is broken first near the hinge on the side away from the operator. Thus the danger to the operator from escaping steam or the like is minimized. On further loosening of the remaining clamps, however, the counterbalancing action comes into play and the cover assumes a horizontal position as described above.

It will be understood that the invention is not restricted to the embodiment particularly described above, and that various changes may be made in the form, details of construction and arrangement of the parts without departing from the spirit of the invention. Reference should therefore be had to the appended claims for a definition of the limits of the invention.

What is claimed is:

1. Apparatus of the class described comprising a container, a cover for said container, means for holding said cover in closed position, means for hinging said cover at the side of said container including a hinge member having a horizontal axis and mounted on said container for vertical movement, means for counterbalancing said cover about said hinge member, and resilient means engaging and lifting said hinge member and with it said cover when the holding means are released.

2. Apparatus of the class described comprising a container, a cover for said container, cooperating tongue and groove means on said cover and container and forming a seal therebetween when the cover is closed, means for holding the cover in closed position, hinge means for said cover at the side of the container and comprising a hinge member having a horizontal axis and mounted on said container for vertical movement relative

thereto, means for counterbalancing said cover about said hinge member, and resilient means engaging and lifting said hinge member and with it said cover to disengage said tongue and groove means when said holding means are released.

3. Apparatus of the class described comprising a container, a cover for said container, means on said cover and container which cooperate to form a seal when the cover is closed, means for holding said cover in closed position, a hinge mounted on said container at one side and comprising a hinge member mounted for limited vertical movement, said cover being pivoted on said member about a horizontal axis, a counterweight connected to the cover on the opposite side of said axis, and resilient means supporting said member and yieldable to permit closing said cover, said resilient means lifting said member and with it said cover and counterweight when said holding means are released to disengage the cooperating sealing means.

4. Apparatus of the class described comprising a container, a cover for said container, means on said cover and container which cooperate to form a seal when the cover is closed, means for holding the cover in closed position, a hinge mounted on said container at one side and comprising spaced brackets, a horizontal hinge pin vertically slidable therein, and resilient supporting means for said pin, said cover being pivoted on said pin and having a counterweight on the opposite side of the pin axis, said supporting means being yieldable to close the cover but lifting the pin, cover and counterweight when said holding means are released to disengage said cooperating sealing means.

5. Apparatus of the class described comprising a container, a cover for said container, cooperating tongue and groove means on said cover and container for effecting a seal when the cover is closed, clamps spaced around the periphery of the container for holding the cover in closed position, a hinge mounted on said cover at one side and comprising spaced vertically-slotted brackets, a horizontal hinge pin vertically movable in the slots, resilient supporting means for said pin, said cover being pivoted on said pin, and a counterweight attached to said cover and disposed on the opposite side of said pin, said supporting means yielding when the cover is clamped in closed position but lifting the pin, cover and counterweight when the clamps are released to disengage said tongue and groove means.
